UNITED STATES PATENT OFFICE.

NAPOLEON DU BRUL, OF CINCINNATI, OHIO.

DESIGN FOR A PLATEN FOR CIGAR-BUNCHING MACHINES.

SPECIFICATION forming part of Design No. 24,779, dated October 22, 1895.

Application filed December 15, 1894. Serial No. 531,974. Term of patent 14 years.

To all whom it may concern:

Be it known that I, NAPOLEON DU BRUL, a citizen of the United States, and a resident of Cincinnati, in the county of Hamilton and State of Ohio, have invented and produced a new and original Design for a Platen for Frames of Cigar-Bunching Machines, of which the following is a specification, reference being had to the accompanying drawing, showing a perspective view thereof.

The leading feature of my design consists in the form or shape of the front portion having the configuration shown.

I represents a platen or table having a down-

wardly-extending front portion 2, a ledge 3, 15 and a downwardly-projecting extension 4 beneath the ledge.

Having thus described my invention, the following is what I claim as new therein and desire to secure by Design Letters Patent: 20

The design for a platen for frames of cigar bunching machines, substantially as herein shown and described.
